WILLIAM NEVINS COOK, OF NEW YORK, N. Y., ASSIGNOR TO E. B. MEYROWITZ, INC., A CORPORATION OF NEW YORK.

GOOGLES.

Application filed November 1, 1924. Serial No. 747,168.

This invention relates to goggles and particularly to the construction of the cushions, forming a part thereof, for engagement with the head of the wearer. Heretofore, such 5 cushions have been formed in endless rings by joining together the ends of a strip of rubber tubing, the abutting ends telescoping over a short piece of tubing of smaller diameter in order to complete the continuous ring. 10 Rubber tubing has been unsatisfactory for this purpose for the reason that the tubing hardened after standing for some time, and thus lost its resiliency and, if it was held in a distorted position, such as by having 15 creases therein, for any considerable length of time, such creases would remain in the tubing. Furthermore, the resiliency of the cushion was very materially decreased at the junction between the ends forming the end- 20 less ring by reason of the enclosed extra piece of tubing, and this was objectionable because the pressure on the wearer's head from the cushions was not uniform. It is also desirable that the cushions have a maxi- 25 mum contact surface at the portions engaging the sides of the nose, and to obtain this with a minimum of weight and obstruction to vision was not possible with the cushions formed of tubing, since it is difficult to 30 manufacture tubing of non-uniform cross section.

An object of this invention is to provide improved cushions for goggles which will have a minimum weight and a maximum 35 effective cushion surface at the ends adjoining the nose piece; which will have uniform resiliency throughout; which will have longer effective life; and which will be less expensive.

40 Various other objects and advantages will be apparent from the following description of an embodiment of the invention, and the novel features will be particularly pointed out hereinafter in claims.

45 In the accompanying drawing:—

Fig. 1 is an inside elevation of a pair of goggles, having attached thereto cushions constructed in accordance with the invention;

50 Fig. 2 is a plan of the same with one of the eyepieces and cushions sectioned through the center; and

Fig. 3 is an elevation of one of the cushions before application to the eyepiece.

In the illustrated embodiment of the invention, the eyepiece frames 1, carrying the lenses or transparent elements 2, are connected by the usual extensible nosepiece 3, so that the pupillary distance may be varied when the goggles are fitted upon different 55 people. The free ends of the eyepiece frames are provided with the usual strap connections 4 by which the goggles may be supported from the head before the eyes. The cushions 5 are each provided with a 60 flange 6 around one side, by means of which they may be secured to the eyepiece frames, the flanges 6 overlapping with corresponding flanges on the eyepiece frames. The flanges 6 may be secured to the frames in any suit- 65 able manner such as by stitching, as hereto- 70 fore.

The cushions 5, in accordance with this invention, are formed of what is known as sponge rubber, and are molded in integral 75 continuous rings with the integral securing flange 6. When so molded, the surface of the ring may be smooth and the interior of it, as in all sponge rubber, will be porous, so that the ring will have considerable elas- 80 ticity and resiliency. Sponge rubber does not readily harden in use, and by reason of its texture, will retain its shape and resiliency, even though it may be held under pressure or distortion for considerable in- 85 tervals. Inasmuch as it is molded in a continuous ring, it will have uniform resil- 90 iency throughout, so that the pressure upon the wearer's head or face will be uniform.

The ring is preferably formed of greater 90 cross sectional area at one point than at another, the cross section tapering between the points of major and minor cross sectional dimensions which are diametrically opposite 95 one another. When viewed in the position of Fig. 3, the circles which outline the inner and outer elements or margins of the annulus are eccentric with respect to each other. The rings are connected to the eyepiece frames with the points of greater cross sectional area 100 of the rings adjacent the nose bridge piece 3, so that the point of maximum thickness is positioned at an angle from the vertical by an amount determined by trial and in accordance with the position of the wearer's 105 eye-hollows and so that they will fit snugly against the sides of the nose and in the eye- 110 hollows beside the nose, and form a more ef-

fective seal against the entrance of air or flying objects. At the outer ends of the eyepieces, it is not necessary to provide as effective a seal, for reasons that are well known.

5 At those points the ring need not be enlarged, and, therefore, the weight and bulkiness, as well as the cost, of the cushion may be reduced. The rings may be molded in circular shape for the purposes of simplicity, but will 10 be elongated slightly when attached to the eyepieces so as to conform to the usual elliptical configuration thereof. Being molded in a circular form, and then being distorted by tension into an elongated form to match the 15 outline of the goggle lens, the rings are readily adjusted with the larger section thereof in an advantageous position with respect to the goggle lens, so as to obtain a maximum accuracy of fit and tightness of seal between 20 the cushion and the wearer's face.

Goggles of this type are commonly worn by aviators, or others subjected to air moving at a considerable velocity directly in their face, and it has been found that goggles constructed in accordance with this invention, and with the large cushioned surface fitting at the sides of the nose, will more effectively and closely fit noses of different configurations. Consequently, the more perfect seal 25 will prevent the air or flying objects from reaching the wearer's eyes. Goggles with such cushions are more comfortable to the wearer since there are no abrupt changes in resiliency, and the durability of the cushions is greater than in prior constructions. When the cushions were made of tubing, two operations were required, first the molding of the said tubing, and then the converting of strips of the same into endless 30 rings. In accordance with this invention but a single molding operation is required for the finished article, which greatly reduces the cost and at the same time provides a more perfect product. This construction is 35 particularly advantageous because of the accuracy with which the cushion can be fitted to a wearer's face, with the larger portion of the circumference adjusted into the deeper hollows in the wearer's face beside his nose.

40 The construction has the further important advantage that it is readily adjustable to fit the faces of different users. Among aviators, each, of course, likes to retain his own pair of goggles, however, it is readily possible, by the construction above disclosed, 45 after transfer of the goggles from one user to another, for the second user to re-adjust the cushions to fit the particular location of the hollows in his own face. This he may do 50 by simply removing the stitching, re-positioning the cushion to suit the contours of his own face, and then re-stitching in that position.

It will be understood that various changes 55 in the details, which have been herein

described and illustrated for the purpose of explaining the nature of the invention, may be made by those skilled in the art within the principle and scope of the invention as expressed in the appended claims.

70

I claim:

1. A resilient cushion for attachment to an eye-piece frame of a pair of goggles, comprising an elongated integral ring member formed of sponge rubber and having a varying cross section, and means cooperating therewith, and comprising removable stitching, whereby the larger section of said cushion is adapted to be adjusted in a facial hollow, attached to a goggle frame.

80

2. A sealing cushion for a goggle lens frame comprising a sponge rubber member of round form having different thickness at different points thereon and having a stitching lip integral therewith and upon one face thereof, adapted to be adjustably and removably attached to a goggle frame.

85

3. A goggle comprising a main frame portion and a stitching edge, and a cushion means comprising a round member formed of sponge rubber of different thickness at different portions of the circumference, with an integral stitching lip adapted to cooperate with the stitching edge upon said goggle frame, and means, comprising removable stitching, for holding said cushion member with its maximum thickness in a position suitable for one wearer and permitting adjustment of the maximum thickness to another position to fit another wearer.

90

4. A resilient cushion for attachment to an eye piece frame of a pair of goggles, comprising an annular ring member formed of resilient material and having a varying cross sectional area at various points around the periphery thereof, whereby certain portions of the annulus are larger than other portions, and means for the attachment thereof to said eye piece frame in an adjusted position.

105

5. A resilient cushion for attachment to an eye piece frame of a pair of goggles, comprising an annular ring member of resilient material, of which the circles outlining the inner and outer margins of the annulus are respectively eccentric, whereby the cross sectional area of the annulus is at a maximum and at a minimum at diametrically opposite points.

110

6. A resilient cushion for attachment to an eye piece frame of a pair of goggles, comprising an annular ring member, of which the circles outlining the inner and outer margins of the annulus are respectively eccentric, whereby the cross sectional area of the annulus is at a maximum and at a minimum at diametrically opposite points, and the cushion is adapted to be adjustably positioned with respect to the ridges and hollows of a wearer's face for the production of an

120

125

air seal between said frame and the face, and means for attaching the cushion to the frame in an adjusted position.

7. A resilient cushion for attachment to an eye piece frame of a pair of goggles, comprising an annular ring member, of which the circles outlining the inner and outer margins of the annulus are respectively eccentric, whereby the cross sectional area of the annulus is at a maximum and at a minimum at diametrically opposite points, and the cushion is adapted to conform to the ridges and hollows of a wearer's face for the production of an air seal between said frame and the face, and means for attaching the cushion to the frame in an adjusted position, comprising an integral auxiliary member adapted for connection to the frame.

8. In a goggle construction, the combination with the lens frames of resilient cushions adjustably attached to said frames, said cushions comprising annular rings of varying cross sectional area, those portions of the rings having the larger cross section being adapted to be positioned at the points of deepest depressions of the wearer's face.

9. In a goggle construction, the combination with the lens frames of cushions of resilient material attached to said frames, said cushions comprising annular rings of varying cross sectional area, and means for adjusting said cushions with respect to said frames so that the larger cross-sectional areas may be positioned at points of deeper depressions of the wearer's face.

10. A cushion for attachment to an eye piece frame of a pair of goggles to surround the wearer's eye, consisting of a sponge rubber ring, the cross sectional area of which varies at different points along its periphery, whereby it is adapted by rotary adjustment to fit the faces of different persons.

11. A goggle comprising a pair of lens frames and cushions attached thereto, said cushions being rings of resilient material of varying cross sectional area at various points around the periphery thereof, means for adjusting the cushions angularly with respect to their axes and means for adjusting the cushions toward and away from each other.

12. A cushion for attachment to an eye piece frame of a pair of goggles to surround the wearer's eye, consisting of a ring of resilient material of varying cross sectional area at different points around its periphery, whereby it is adapted by rotary adjustment to fit the faces of different persons.

13. A resilient cushion for attachment to an eye piece frame of a pair of goggles, comprising a ring having a varying cross sectional area, an impervious surface, and a cushioned interior body, and means co-operating therewith, whereby that portion of said cushion of greater cross sectional area may be adjusted relatively to the eye piece frame to fit a facial hollow, attached to a goggle frame.

In witness whereof, I hereunto subscribe my signature.

WILLIAM NEVINS COOK.
